[57] CLAIM

The ornamental design for room divider upper cover lining, as shown and described.

DESCRIPTION

FIG. 1 is a perspective view of a room divider upper cover lining showing my new design;

FIG. 2 is a front elevational view thereof; a rear elevational view is same as a front elevational view;

FIG. 3 is a left side elevational view thereof; a right side elevational is same as a left side elevational view;

FIG. 4 is a top plan view thereof;

FIG. 5 is a bottom plan view thereof; and,

FIG. 6 is perspective view thereof.

The broken lines showing a panel is for illustrative purposes only, and form no part of the claimed design.
